Primary Examiner — Mary Ann Calabrese*Assistant Examiner* — Megan M Majcher Hartnett(74) *Attorney, Agent, or Firm* — Eric L. Sophir; Dentons US LLP(57) **CLAIM**

An ornamental design for a display screen with graphical user interface, as shown and described.

DESCRIPTION

The sole FIGURE is a front view of a display screen with graphical user interface.

The broken lines showing of the display of an electronic device illustrate unclaimed environments, and form no part of the claimed design. The long dash dot style broken line indicates a boundary that forms no part of the claimed design.
